SHAKE-OUT APPARATUS FOR FOUNDRY FLASKS

Walter F. Piper, Oak Park, Ill., assignor to The Beardsley & Piper Company, Chicago, Ill., a corporation of Illinois

Application February 20, 1933, Serial No. 657,511

6 Claims. (Cl. 259—72)

The present invention relates generally to shake-out apparatus for foundry flasks. More particularly the invention relates to that type of flask shake-out apparatus which effects shake-out of the flask by vibrating the latter at comparatively high speed and includes as the operating part thereof, a flask vibrating device which consists of a cylinder, a slidably mounted hammer in one end of the cylinder, and a pneumatically operated piston in the other end of the cylinder for imparting blows in rapid succession to the hammer for flask vibrating purposes.

10 One object of the invention is to provide an apparatus of this type in which the hammer of the vibrating device is designed to engage directly and form a rest or support for the flask and during operation of the device transmits vibrations directly to the flask without jarring or transmitting shock to the cylinder of the device.

Another object of the invention is to provide a flask shake-out apparatus of the type under consideration which comprises a supporting structure and a plurality of vibrating devices which are supported on the supporting structure in horizontally spaced relation and in an up-standing position and are arranged so that the hammers thereof engage different portions of the flask.

30 A further object of the invention is to provide a flask shake-out apparatus of the last mentioned character in which the hammers of the vibrating devices have enlarged, rounded heads for tiltably sustaining or supporting the flask and the supporting structure is provided between the vibrating devices with a bar for limiting tilting of the flask and holding it in place on the heads of the hammers.

40 A still further object of the invention is to provide a flask shake-out apparatus of the type and character under consideration which is generally of new and improved construction, consists of but a small number of parts and may be manufactured at a low and reasonable cost.

45 Other objects of the invention and the various advantages and characteristics of the present shake-out apparatus will be apparent from a consideration of the following detailed description.

50 The invention consists in the several novel features which are hereinafter set forth and are more particularly defined by claims at the conclusion hereof.

55 In the drawings which accompany and form a part of this specification or disclosure and in

which like numerals of reference denote corresponding parts throughout the several views Figure 1 is a side elevation of an apparatus embodying the invention. Fig. 2 is a plan. Fig. 3 is a vertical section through one of the vibrating devices. Fig. 4 is an end elevation of the vibrating device of Fig. 3. Fig. 5 is a fragmentary plan view of a modified form of a flask shake-out apparatus.

The shake-out apparatus of Figures 1, 2, 3 10 and 4 comprises a pair of channel beams 10 which are adapted through the medium of a pair of vibrating devices 12 to support a flask 18 and are secured on the top of a grating 11 through which the sand discharged from the flask is 15 adapted to fall into a pit or onto the floor. The vibrating devices 12 are of like construction. They are secured on top of and between the channel beams 10 and are positioned to underlie opposite side-rails of the flask 18.

20 Each vibrating device comprises a casing 13 in which is formed a vertical cylinder 14 adapted to receive air under pressure; a piston 15 slidable in the cylinder 14; and a hammer 16 provided with a stem 16^a slidably fitted in the 25 upper end of the cylinder 14 and adapted to be impacted or struck by the piston 15, and also provided with an enlarged head 16^b positioned above the casing and outside of the cylinder. The casing 13 is provided with integral lugs 30 13^a for bolts 17 which are adapted to secure the casing in fixed position on the beams 10.

The sides of flask 18 are adapted to rest directly on the tops of the heads 16^b of the hammers 16 of the vibrating devices. These heads 35 are positioned over the top walls of the cylinders 14 and are adapted normally to rest on said walls. An attribute of this construction is that the flask rests on and is directly supported by the hammers, so that the blows imparted to the 40 hammers will be transmitted directly to the flask and not to the casings of the vibrating devices. The top surfaces of the head 16^b are convex to permit the flask to rock during blows by the hammers. A bar 19 with upstanding lugs 45 19^a at its ends is welded to the beams 10 and extends transversely of the beams 10 and under the flask a sufficient distance to prevent the flask from tilting transversely off the heads of the hammers. The flask is confined against dis-

placement longitudinally of the beams 10 by vertical guide plates 20 which are secured to the casings 13 by certain of the bolts 17. This exemplifies an apparatus for shaking out a foundry flask in which the flask rests directly on the 55

hammer heads which are vibrated as hereinafter set forth, so that the blows imparted to the hammers will be transmitted directly from the hammers to the flasks to dislodge more effectively the material from the flask. It also exemplifies means for retaining the flask on the hammer heads so they will not be displaced during vibration of the flask.

Each vibrating device is operable by fluid under pressure, preferably air, which is delivered into an inlet-chamber 21 in the casing 13 through a pipe 22 which is suitably connected, usually by a flexible hose, to a source of compressed air. The piston 15 is provided with two circumferential grooves 15^a and 15^b, which form, in effect, three piston-sections 15^a, 15^b and 16^a. The upper end of the piston is adapted to impact against the lower end of the stem 16^a of the hammer 16 to impart blows in rapid succession to the hammer. Ports 24 extend axially through the piston-section 15^b and ports 25 extend axially through the piston-section 15^a. An annular inlet channel 21^a formed in the casing around the cylinder 14 is in communication with the inlet-chamber 21. Annular exhaust-channels 25^a and 26 are formed in the cylinder wall and lead to an exhaust-chamber 27. Assuming the piston 15 to be in the position shown in Fig. 3, air under pressure will flow from channel 21^a into the groove 15^a in the piston and through ports 24 to exert a pressure upon the piston to impart an upward stroke to the piston and a blow to the lower end of the hammer-stem 16^a. During this stroke, the piston-section 15^b will cut off the supply of compressed air. After the blow has been struck, the air which has imparted the upward stroke to the hammer will escape through channel 25^a and groove 15^a to the exhaust chamber 27. As the hammer reaches its upward limit, air will flow from inlet-chamber 21 through a small port 28 into groove 15^b of the piston to exert a downward pressure on the top of section 15^b and the top of section 15^a to which air passes via ports 23, to return the hammer to its lowered position. During the return stroke, the air from the top of the piston will be passed through ports 25, groove 15^b and channel 26 to the exhaust chamber 27. This operation is repeated in rapid succession to impart the blows to the hammer to vibrate the flask.

A sheath of flexible material, such as asbestos belting, is fitted around the periphery of the head 16^b of each hammer and depends around the outside of the upper portion of the cylinder, to prevent sand from passing into the cylinder. This sheath is secured to the head of the hammer by a binding wire 31 which ties the sheath in an annular groove 32 in the head of the hammer.

Fig. 5 shows a slightly different form of shake-out apparatus in which provision is made for adjustably mounting one of the vibrating devices so it can be adjusted to and from the other to adapt the apparatus for flasks of different widths. In this form of apparatus, a link 34 has one of its ends pivoted to the casing of the movable device and its other end to a lever 35 which is pivoted to one of the channel beams 10. The top flanges of the beams 10 are provided with a plurality of bolt holes for the bolts 17. When the bolts 17 are removed, the movable vibrating device can be shifted by the lever 35 longitudinally of the beams to bring it into the desired position according to

the width of the flask and the bolts 17 can then be passed through the aforesaid bolt holes to lock the vibrating device in its desired position.

The invention exemplifies a flask shake-out apparatus in which the flask rests directly on a fluid operated hammer so that the blows imparted to the hammer by the piston will be imparted directly to the flask and in this way the flask is sharply and efficiently vibrated to cause the material or castings therein to be dislodged from the flask. If desired, the invention may be used with a single vibrating device or more than two.

The invention is not to be understood as restricted to the details set forth since these may be modified within the scope of the appended claims without departing from the spirit and scope of the invention.

I claim:

1. In a flask shake-out apparatus of the character described, the combination of a supporting structure; a vibrating device mounted in an upstanding position on the structure and comprising a vertical cylinder with an open upper end, a hammer slidably mounted in the upper end of the cylinder and embodying at the top thereof an enlarged rounded head for supporting the flask directly thereon and so that it is tiltable relatively to the device; a piston in the lower end of the cylinder; and fluid pressure means for moving the piston up and down in rapid succession in order to impart blows to the hammer so as to transmit vibrations via the head directly to the flask; and bar means mounted on the supporting structure independently of the vibrating device for limiting tilting of the flask and holding it in place on the head.

2. In a flask shake-out apparatus of the character described, the combination of a supporting structure; a flask vibrating device mounted on the structure and comprising a cylinder with one end thereof open and its other end closed; a piston slidably mounted within the closed end of the cylinder; fluid pressure means for reciprocating the piston in rapid succession within said closed end of the cylinder; and a slidably mounted hammer in the open end of the cylinder provided at the outer end thereof with a fully exposed rigid head for engaging directly a portion of the flask; and adapted during reciprocation of the piston to receive blows from the latter and to transmit such blows via the head directly to the flask without imparting shock to the cylinder; and means associated with the supporting structure and independent of the hammer for holding the flask in a shake-out position with respect to said head.

3. In a flask shake-out apparatus of the character described, the combination of a supporting structure, a flask vibrating device mounted in an upstanding position on the structure and comprising a substantially vertical cylinder with an open upper end, a piston slidably mounted in the lower end of the cylinder; fluid pressure means for moving the piston up and down in rapid succession in said other end of the cylinder, and a slidably mounted hammer in the upper end of the cylinder provided at the outer end thereof with a fully exposed, enlarged, rounded head for supporting the flask directly thereon and so that it is tiltable relatively to the device and adapted during reciprocation of the piston to receive blows from the

latter and to transmit such blows via the head directly to the flask without imparting shock to the cylinder; and means independent of the hammer for limiting tilting of the flask and holding the flask in direct engagement with and in place on the head.

4. In a flask shake-out apparatus of the character described, the combination of a supporting structure; a pair of laterally spaced, vibrating devices mounted vertically on the supporting structure and adapted to support the flask, each of said devices comprising an upstanding cylinder with an open upper end, a hammer slidably mounted in the upper end of the cylinder and embodying at the top thereof a rigid head designed and fully exposed to engage directly a portion of the flask, and a pneumatically operated piston in the lower end of said cylinder adapted to move up and down in rapid succession and to impart blows to the hammer so as to transmit vibrations to the flask via the head; and bar means mounted on the supporting structure between the two devices and entirely independent of the said devices for engaging the flask loosely and holding it in direct engagement with and in place on the heads.

5. In a flask shake-out apparatus of the character described, the combination of a supporting structure; a pair of laterally spaced vibrating devices mounted vertically on the supporting structure and adapted to support the flask, each of said devices comprising an upstanding cylinder with an open upper end, a hammer slidably mounted in the upper end of the cyl-

inder and embodying at the top thereof an enlarged head designed and fully exposed to engage directly one of the end portions of the flask, and a pneumatically operated piston in the lower end of said cylinder adapted to move up and down in rapid succession and to impart blows to the hammer so as to transmit vibrations to the flask directly through the head; and means mounted on the supporting structure between the two vibrating devices for engaging the side portions of the flask and supporting the flask loosely and holding it in place on the heads of said devices.

6. In a flask shake-out apparatus of the character described, the combination of a supporting structure; a pair of laterally spaced, vibrating devices mounted vertically on the supporting structure and adapted to support the flask, each of said devices comprising an upstanding cylinder with an open upper end, a hammer slidably mounted in the upper end of the cylinder and embodying at the top thereof an enlarged rounded head for engaging a portion of the flask directly and supporting the latter so that it is tiltable relatively thereto, and a pneumatically operated piston in the lower end of said cylinder adapted to move up and down in rapid succession and to impart blows to the hammer so as to transmit vibrations to the flask via the head; and bar means mounted on the supporting structure between the vibrating devices for limiting tilting of the flask and holding the latter in place on the heads of said devices.
